APPLICATOR

Leonard Abbotts, Bridgeport, Conn., assignor to
 The Bridgeport Metal Goods Manufacturing
 Company, Bridgeport, Conn., a corporation of
 Connecticut

Application October 25, 1934, Serial No. 749,987

8 Claims. (Cl. 91—67.4)

This invention relates to new and useful improvements in applicators, and has particular relation to applicators of the type including a glass rod which are used in applying perfumes, glass rod which are used in applying perfumes, 5 antiseptics, etc.

The essential oils, alcohols, and the like of perfumes, etc. loosen up or destroy cement and rot rubber, so that in applicators wherein the applicator rod, usually of glass, is cemented to a stopper or forced into a rubber stopper the rod soon becomes loose with respect to the stopper and frequently drops from the stopper into the bottle of perfume or the like, and must be fished out at great inconvenience, or the bottle and its 10 contents thrown away.

An object of the invention is to provide an applicator including a glass rod and a bottle closure wherein the glass rod is mechanically connected or secured to the closure, whereby the 20 essential oils and alcohols of perfumes cannot loosen the glass rod with respect to the closure.

Other objects and advantages will become apparent from a consideration of the following detailed description taken in connection with the 25 accompanying drawing wherein satisfactory embodiments of the invention are shown. However, it will be understood that the invention is not limited to the details disclosed, but includes all such variations and modifications as fall within the spirit of the invention and the scope of the appended claims.

In the drawing:

Fig. 1 is a view partly in elevation and partly in section showing the improved applicator in place 35 on a bottle;

Fig. 2 is a sectional view taken substantially along the plane of the line 2—2 of Fig. 1;

Fig. 3 is a sectional view taken substantially along the line 3—3 of Fig. 1;

Fig. 4 is a greatly enlarged sectional view illustrating a step in assembling the applicator;

Fig. 5 is a somewhat similar view on the same scale and showing the mechanical clamping of the glass rod in an eyelet employed;

Fig. 6 is a view partly in section and partly in elevation showing the outside cap of the closure;

Fig. 7 is a similar view of a tubular eyelet used;

Fig. 8 is a side elevational view of said eyelet;

Fig. 9 is an elevational view of the glass rod;

Fig. 10 is a view partly in elevation and partly in section of an inner shell used;

Fig. 11 is a similar view of a cork ring or seal;

Fig. 12 is a similar view of the upper or neck 55 portion of a bottle;

Fig. 13 is a view similar to Fig. 4 but showing a modification;

Fig. 14 is a view somewhat similar to Fig. 5 but illustrating the modification of Fig. 13; and

Fig. 15 is a view partly in section and partly in elevation and showing the eyelet of Figs. 13 and 14 in place on a glass rod.

Referring in detail to the drawing, and at first particularly to Figs. 1 through 12, the improved applicator generally designated 10 is shown as 10 including a glass rod 11 and a bottle closure 12 mechanically secured to said glass rod as will later more fully appear. In Fig. 1 the applicator is shown as applied to a bottle 13 including a neck portion 14 having a screw thread or spiral 15 groove 16 therein. It will later become evident that the applicator need not take the particular form shown and that its use is not limited by any particular bottle construction.

In assembling the applicator an eyelet 16 including a tapered tubular body portion 17 having a radial flange 18 at one of its ends is used. The glass rods 11 vary in diameter and are first assembled in the eyelets 16. To take care of rods of different diameters one or more nubs 19 are 25 pressed inwardly from the sides of the body portion of the eyelet 16 and the nubs or nub extend inwardly to such distance that the diameter of the eyelet body between the nubs is less than the diameter of the rod 11. Then, the rod is forced into 30 the eyelet as suggested in Fig. 4, where it will be noted that the rounded end of the rod is just entering between a pair of the nubs 19. As the rod is forced through the eyelet the nubs 19 yield outwardly but tightly hold or grip the rod so 35 that it is firmly attached to the eyelet. Fig. 5 shows the rod in place in the eyelet, and it will be noted in this figure that the nubs 19 have been forced to yield outwardly as compared with their positions in Fig. 4. With this method of as- 40 sembling the rod in the eyelet the eyelet is prepared to receive rods of varying diameters since the nubs are pressed inwardly to a greater extent than is necessary and the rods must be forced through the eyelets causing the nubs to yield 45 outwardly where they tightly grip or hold the rod. Although these rods are usually of glass it will be understood this means of mounting is not limited to use with rods of this material but may be used with any suitable material. 50

When the eyelet has thus been secured to the rod the rod is forced through the eyelet until the upper or outer end of the rod is about flush with the flange portion 18 of the eyelet. Thereafter an inner shell 20 carrying a perforated washer or 55

ring 24 of cork or other suitable sealing material is passed over the rod 11 from the inner or rounded end thereof. This shell is open at its inner end and in its side wall 21 is provided with 5 a screw thread 22 pressed or rolled therein and at its outer end is provided with an inwardly curved flange portion 23. As the shell 20 is slipped into place the free end of the rod passes through the shell and the flange 23 of the shell is brought 10 into engagement with the underside of the flange 18 of the eyelet 16 as shown best in Fig. 1. The eyelet fills the opening through the flanged end of the shell so that the latter is held in concentric relation with respect to the eyelet and the rod 11. 15 The opening in the washer or ring 24 of cork or the like is somewhat smaller than the eyelet so as to fit tightly about the tubular portion of the eyelet, and this washer has a forced or tight fit between the tubular portion of the washer and 20 the skirt-like side wall 21 of the shell 20. Next, a cap 25 including a side wall 26 and an end wall 27 is forced over the inner shell 20. The cap 25 may be of metal or other suitable material and has a forced fit with respect to the shell so that 25 when the cap is in place it is rigidly secured to the shell. Further, when the cap is in place its end wall 27 is against the radial flange 18 of the eyelet so that said flange of the eyelet is clamped or held between the flange 23 of the inner shell and 30 the end wall 27 of the cap.

It will now be understood that the glass rod 11 is mechanically secured to the eyelet 16 and that there is no cement or other adhesive used to secure these parts together. The nubs 19 have 35 been forced to yield outwardly by the rod 11 and consequently tightly grip or hold said rod so that there is no likelihood of it falling out of the eyelet. Further, the flange 18 of the eyelet is of greater diameter than the opening through the flanged 40 end of the shell 20 so that the eyelet cannot move entirely through the shell, and the said flange of the eyelet is clamped between the flange 23 of the shell 20 and the end wall 27 of the cap 25.

Since the said cap 25 has a forced fit over the 45 shell 20 it will be appreciated that these parts are rigidly connected and that they are connected without the use of cement or the like, and that the flange 18 of the eyelet being mechanically clamped or held between the flange 23 of the shell 20 and the wall 27 of the cap 25 there is no cement or other material to become loosened or dissolved by the essential oils or alcohols in the 50 contents of the bottle. Further, if cork is used as the sealing material, there is no rubber to rot and 55 release the rod 11. However, if the applicator is to be used with liquids that do not affect rubber this may be used as the sealing material if desired. The applicator is applied to the bottle by inserting the glass rod 11 into the bottle neck and 60 then threading the applicator into place by engagement of its thread 22 with the thread 15 on the bottle neck. This serves to draw the cork or other ring 24 against the outer end of the bottle neck forming a tight seal.

65 Figs. 13, 14, and 15 illustrate a slight modification of the eyelet construction, and the eyelet of these figures may be used when the supply of glass rods received comprises or includes rods of unusually small diameter. In these figures the 70 eyelet is generally designated 28 and at its outer or upper end is provided with the usual flange 18 and may in its body portion be pressed inwardly at one or more points to provide the nubs 19 as and for the purpose above explained. Additionally the lower or inner end portion is reduced as

by pressing or rolling to provide a bead 30 at the inner side of the body portion 29 of the eyelet. This bead 30 reduces the inner diameter of the eyelet very materially and to such an extent that the inner diameter of the eyelet at the bead is less than the diameter of the small rods on which the eyelet is to be assembled.

Fig. 13, on a greatly enlarged scale, shows the rounded or inner end portion of the rod 11 just entering the bead 30 of the eyelet 28, and the rod 10 is forced through the eyelet causing the bead to yield outwardly somewhat into the position of Fig. 14 where the body portion of the glass rod is shown extending through the bead 30 of the eyelet. It will be clear that this bead portion of the 15 eyelet is tightly gripping the rod so that there is no likelihood of the rod and eyelet separating, and if the eyelet is also provided with the nubs 19 there is an additional securing of the eyelet to the rod. It is not necessary that the eyelet in 20 each instance be provided with both the bead 11 and the nubs 19 since as shown in the Figures 1 through 12 the nubs alone are used. The nubs 19 might be omitted from the eyelet 28 of Figs. 13 through 15, and this eyelet may be secured to the 25 rod solely by the internal bead portion 30 of the eyelet gripping the rod. It is to be understood that the rod with the eyelet 28 is to be secured to a closure including the shell 20 and the cap 25 and the cork or other seal 24 as in the figures first 30 described. Therefore, in the modified construction the parts are mechanically connected and no cement or the like is employed.

Having thus set forth the nature of my invention, what I claim is:

1. In an applicator, a rod, an eyelet on one end portion of the rod and including a tubular portion through which the rod extends and a radially extending flange at one end of said tubular portion, said tubular portion of the eyelet having an 40 inwardly pressed portion causing gripping of the rod by the eyelet, a shell including an internally screw threaded skirt-like wall portion to engage the neck of a bottle and a flange engaging the under side of the flange of the eyelet, a sealing 45 ring about the tubular portion of the eyelet and having a forced fit between the said eyelet portion and the skirt-like wall of the shell, and a cap including side walls having a forced fit over the wall of the shell and an end wall engaging 50 the outer surface of the flange of the eyelet whereby said flange is held between the end wall of the cap and the flange of the shell.

2. In an applicator, a rod, an eyelet on one end portion of the rod and including a tubular 55 portion through which the rod extends and a radially extending flange at one end of said tubular portion, said tubular portion of the eyelet having an inwardly pressed portion causing gripping of the rod by the eyelet, a shell including an internally screw threaded skirt-like wall portion to engage the neck of a bottle and a flange engaging the under side of the flange of the eyelet, and a cap including side walls having a forced fit over the wall of the shell and an end wall engaging the 60 outer surface of the flange of the eyelet whereby said flange is held between the end wall of the cap and the flange of the shell.

3. In an applicator, a rod, an eyelet on one end of the rod and including a tubular portion through 70 which the rod extends, said tubular portion of the eyelet being for the greater portion of its length of a larger internal diameter than the diameter of the rod and having an inwardly pressed portion causing gripping of the rod by the eyelet, and 75

a closure for a bottle neck secured to said eyelet.

4. In an applicator, a rod, an eyelet on one end portion of the rod and including a tubular portion through which the rod extends and a radially extending flange at the outer end of said tubular portion, said tubular portion of the eyelet being tapered inwardly from the flange and of larger internal diameter than the rod except adjacent its free end, said tubular portion also having an inwardly pressed portion spaced from said free end causing gripping of the rod by the eyelet, and a bottle neck closure including a pair of rigid portions receiving the flange of the eyelet between them and secured to the rod thereby.

5. In an applicator, a rod, an eyelet on one end portion of the rod and including a tubular portion through which the rod extends and a radially extending flange at one end of said tubular portion, said tubular portion of the eyelet being of a larger internal diameter than the rod except at its free end where it is of a diameter to grip the rod, said eyelet also having an inwardly pressed portion spaced from the free end causing gripping of the rod by the eyelet, and a bottle neck closure receiving the flange of the eyelet and secured to the rod thereby.

6. In an applicator, a rod, an eyelet on one end portion of the rod and including a tubular portion through which the rod extends and a radially extending flange on said tubular portion, said tubular portion of the eyelet having nubs pressed inwardly reducing the inner diameter of the tubu-

lar portion at the nubs to less than the diameter of the rod whereby when the rod is inserted into the eyelet it forces the nubs outwardly and the rod is tightly held thereby, and a bottle neck closure clampingly receiving the flange of the eyelet and secured to the rod thereby.

5

7. In an applicator, a rod, an eyelet on one end portion of the rod and including a tubular portion through which the rod extends and a radially extending flange at one end of said tubular portion, said tubular portion having its other end portion rolled inwardly providing an inner bead of less diameter than the rod whereby when the rod is inserted in the eyelet it forces the bead outwardly and is tightly held thereby, and a bottle neck closure clampingly receiving the flange of the eyelet and secured to the rod thereby.

10

8. In an applicator, a rod, an eyelet on one end portion of the rod and including a tubular portion through which the rod extends and a radially extending flange on said tubular portion, said tubular portion of the eyelet having nubs pressed inwardly reducing the inner diameter of the tubular portion at the nubs to less than the diameter of the rod and having its end portion opposite its flange rolled inwardly providing an inner bead of less diameter than the rod whereby the rod is forcing the nubs and bead outwardly and is tightly held, and a bottle neck closure clampingly receiving the flange of the eyelet and secured to the rod thereby.
